UNITED STATES PATENT OFFICE.

JAMES VRBA, OF MARSHALLTOWN, IOWA, ASSIGNOR TO LENNOX FURNACE COMPANY, MARSHALLTOWN, IOWA.

FURNACE-DAMPER DEVICE.

Application filed November 24, 1924. Serial No. 751,959.

In the construction of modern furnaces, there is ordinarily a combustion chamber, a radiating drum between the combustion chamber and the flue, and a furnace casing surrounding both the combustion chamber and the radiating drum from which the hot air pipes are extended. In furnaces of this class it is customary to provide a damper device by which the products of combustion 5 may be permitted to pass directly from the combustion chamber to the flue when the damper is opened, or such products may be compelled to circulate through the radiating drum before passing to the flue when the 10 damper is in its closed position. These dampers are at times subjected to intense heat and after being installed are not conveniently accessible, and if any leakage should occur around the damper stem, 15 burned products of combustion would pass into the furnace casing and from there be circulated through the building being heated, with obvious undesirable results.

My object is to provide a damper device 20 of simple, durable and inexpensive construction formed complete of simple castings and without machine work, and which may be readily, quickly and easily installed, and not readily impaired or burned out by excessive 25 heat; and

Further my object is to provide a device of 30 this kind in which the escape of products of combustion around the damper stem is prevented.

My invention consists in the construction, 35 arrangement and combination of the various parts of the device, whereby the objects contemplated are attained, as hereinafter more fully set forth, pointed out in my claims, and 40 illustrated in the accompanying drawings, in which:

Figure 1 shows a perspective view of a portion of a furnace with my improved 45 damper device installed therein.

Figure 2 shows an enlarged detail view of a portion of the deflector plate of a radiating drum with my improved damper device installed therein with the damper in open position.

Figure 3 shows a similar view with the 50 damper in a closed position.

Figure 4 shows a vertical sectional view on the line 4-4 of Figure 3.

Figure 5 shows a top elevation of my improved damper device with the damper con-

trolling plate in position with the damper open.

Figure 6 shows a similar view with the damper regulating plate in the position it would assume with the damper closed; and 60

Figure 7 shows a sectional view on the line 7-7 of Figure 2.

Referring to the accompanying drawings, I have used the reference numeral 10 to indicate generally the furnace combustion chamber and 11 the radiating drum. Surrounding the combustion chamber and the drum is the usual furnace casing 12. From the radiating drum, the flue pipe 13 is extended. The top of the radiating drum is substantially flat and is indicated generally by the numeral 14. Within the radiating drum there is usually provided a cast metal deflector plate 15 having an opening therein. The deflector plate is customarily arranged within the drum 11 between the inlet pipe and the discharge pipe that communicates with the drum, and the opening is so arranged that when it is unobstructed there is substantially a straight passageway through the 70 drum, but when the opening is closed the deflector plate causes the products of combustion passing through the drum to be widely distributed throughout the drum to increase radiation. The shape and positions of said 75 deflector plate vary to a considerable extent. It is, however, in common use and it is believed to be unnecessary to more fully and particularly illustrate or describe it.

In the construction of the deflector plate I 80 provide at the bottom of the flue opening therein an enlarged tapered socket device 16 having a substantially flat horizontal top, and in the center of the top having a tapered depression, as shown in Figure 4. At the top 85 of the flue opening there is formed in the deflector plate an enlarged cylindrical body 17 having a vertical opening through it, and also having a downwardly extended shoulder 18 at one side. At the margin of the damper 90 opening there is formed a flange 19, as shown in Figure 7, for purposes hereinafter made clear.

The damper proper comprises a body portion 20 having at its lower end a tapering 105 bearing 20^a to receive a pivot pin 20^b, and having at its top a socket shaped to receive an angular damper pin 29, hereinafter described, and formed on one side of the damper near its upper end is a stop device 110

20° designed to engage the shoulder 18 and limit the opening movement of the damper.

Mounted on top of the radiating drum is a valve operating and sealing device comprising a lower circular plate 21 formed with a central opening and also with a raised tapered rib 22 surrounding the central opening, and a circular depression surrounding the rib 22, and with a flat surface extended 10 horizontally outwardly to the exterior of the circular plate 21, as shown in Figure 4. On the under surface of the plate 21 there is a downwardly extended circular flange 23 slightly spaced apart from the 15 central opening, and a downwardly extended flange 24 at the outer edge. Between said flanges 23 and 24 there is formed a dead air chamber 25. This lower plate 21 is permanently connected with the part 14 by bolts 26, and preferably a packing of asbestos, or the like, 27, is provided between the flanges 23 and 24 and the part 14.

Mounted on top of the plate 21 is a second circular plate 28 formed with a central opening in which there is fixedly mounted an angular shaft 29, designed to extend downwardly through the plate 28 through an opening in the plate 21 and the part 14, and through the body portion 17 into an angular recess provided for it in the top of the damper, as shown in Figure 4. This angular recess has an opening at one side of its lower end to permit any fine ashes or dust to pass through to thereby avoid such accumulation thereof as would tend to raise the shaft 29. The lower end of the shaft 28 is shown projected through this opening in Figure 4.

Formed in the under surface of the plate 28 is an annular groove, tapered and designed to fit the rib 22, and surrounding said groove is an annular rib 30 tapered and shaped to fit into the corresponding groove in the upper surface of the plate 21, and at the outer edge of the plate 28 there is a downwardly extended rib 31 to engage the top surface of the plate 21, and between the ribs 30 and 31 there is a dead air space 32 in which the heads of the bolts 26 are received. Extended outwardly from the plate 28 is an arm 33 connected to a rod 34 and extended through the furnace casing front, so that the damper may be adjusted from the front of the furnace.

In practical use the parts are assembled as follows: The plate 21 is bolted to the top of the radiating drum, then the damper is placed in position in the damper opening with the tapered bearing 20^a in the tapered socket 16, then the plate 28 is applied and the shaft 29 extended downwardly until it enters the upper end of the damper, and when in this position the plate 28 will have its tapered rib 30 and its rib 31 both held 60 in frictional engagement with the corre-

sponding parts of the plate 21 by gravity. The rod 34 is then connected to the arm 33, and the device is ready for use.

In use, it is not practical to provide a gas tight joint at the lower ~~end~~⁷⁰ of the damper shaft 29, because of the extreme changes in temperatures to which these parts are subjected. Hence, products of combustion will pass upwardly through the radiating drum surrounding the shaft 29. I am aware that heretofore there has been provided a stationary plate surrounding the upper end of the damper shaft and provided with a tapered annular rib, and on top of it there has been provided a second plate capable of rotation and containing the damper shaft and having an annular tapered groove to receive the annular rib of the lower stationary plate. However, it has been proven impracticable in use to make these tapered joints tight enough under all conditions to maintain gas tight joints. My improvement, however, comprises the extending of the upper and lower plates outwardly to a considerable distance and then forming a downwardly extended rib in the outer surface of the upper plate to engage the top surface of the lower plate and to form a dead air space surrounding the bolt heads therein. I have demonstrated in practice that by this improved construction, and with the use of ordinary castings not machined, I have been able to provide a gas tight joint, for the reason that the said dead air space for the outer flange 31 acts in such a manner as to tend to equalize the pressures on the interior and exterior of the plates 21 and 28 to such an extent as to prevent the escape of gas from the radiating drum of the interior of the furnace casing.

Furthermore, by providing the downwardly extended flange 24 on the lower plate 21, and also providing a dead air space between the said flange 24 and the flange 23, I prevent the escape of gas through the bolt openings.

Another advantage gained by the use of my improved damper device is that the shaft 29 is protected from the intense application of heat by having its upper portion completely surrounded by the enlarged body 17, and its lower portion received into an enlarged socket device 20^b and terminating at a point above the thin body portion of the damper. The lower end of the damper is formed with a cast tapered bearing which provides a bearing at the bottom of the damper. Heretofore it has been customary to connect and support a damper by means of a shaft extended through it and exposed at various points to the action of the heat, and this has resulted in frequent burning out of the exposed portions of said shaft.

With my improvement the entire device

may be made of simple castings which do not need to be machined after casting, and which can be readily, quickly and easily assembled, and which are extremely durable and will prevent the escape of gas into the furnace casing.

I claim as my invention:

1. In a damper control device, the combination of two circular plates, the lower one formed with a central opening and with a raised rib surrounding the opening, an annular groove surrounding the raised rib, an outwardly extended portion beyond said annular groove, and an upper circular plate having an annular groove to receive said annular rib on the lower plate, an annular rib to enter said annular groove in the lower plate, and an outwardly extended portion terminating in a downwardly extended flange to engage the top surface of the outer portion of the lower plate and to form between the two plates a dead air chamber.

2. In a damper control device, the combination of two circular plates, the lower one formed with a central opening and with a raised rib surrounding the opening, an annular groove surrounding the raised rib, an outwardly extended portion beyond said annular groove, and an upper circular plate having an annular groove to receive said annular rib on the lower plate, an annular rib to enter said annular groove in the lower plate, and an outwardly extended portion terminating in a downwardly extended flange to engage the top surface of the outer portion of the lower plate and to form be-

tween the two plates a dead air chamber, said lower plate being also formed with two downwardly extended annular flanges spaced apart from each other, and with bolt openings extended through it between said downwardly extended flanges to form a dead air chamber surrounding said bolt openings.

3. The combination with a radiator drum of a deflector plate formed with a damper opening and having at the bottom of the damper opening an enlarged socket, and also having at the top of the damper opening an enlarged body portion formed with a socket, and a damper body having formed at its lower end a tapered bearing fitted into said socket and having formed at its upper end an enlarged body formed with a pivot pin opening at its upper end, for the purposes stated.

4. The combination with a radiator drum of a deflector plate formed with a damper opening and having at the bottom of the damper opening an enlarged socket, and also having at the top of the damper opening an enlarged body portion formed with a socket, and a damper body having formed at its lower end a tapered bearing fitted into said socket and having formed at its upper end an enlarged body formed with a pivot pin opening at its upper end, said damper being also provided with a stop device formed at one side, and the enlarged body portion therein and being formed with a shoulder for engaging the stop device and limiting the rotary movement of the damper.

JAMES VRBA.
